US00D967783S

(12) **United States Design Patent** (10) Patent No.: **US D967,783 S**
Dimberg et al. (45) Date of Patent: **** Oct. 25, 2022**

(54) **CONTROL DEVICE**(71) Applicant: **Lutron Technology Company LLC**,
Coopersburg, PA (US)(72) Inventors: **Chris Dimberg**, Easton, PA (US);
Jason C. Killo, Emmaus, PA (US);
Noel Mayo, Philadelphia, PA (US);
Matthew Philip McDonald,
Phoenixville, PA (US)(73) Assignee: **Lutron Technology Company LLC**,
Coopersburg, PA (US)(**) Term: **15 Years**(21) Appl. No.: **29/798,920**(22) Filed: **Jul. 12, 2021****Related U.S. Application Data**

(63) Continuation of application No. 29/743,398, filed on Jul. 21, 2020, now Pat. No. Des. 926,712, which is a continuation of application No. 29/697,938, filed on Jul. 12, 2019, now Pat. No. Des. 892,750.

(57)

CLAIM

The ornamental design for a control device, as shown and described.

DESCRIPTION

FIG. 1 is a front perspective view of a control device showing our new design;

FIG. 2 is a front view thereof; and,

FIG. 3 is a side view thereof.

(Continued)

The dashed broken lines illustrate structure or features which form no part of the claimed design.

1 Claim, 2 Drawing Sheets
